UNITED STATES PATENT OFFICE.

FREDERICK J. CLARK, OF SYRACUSE, NEW YORK.

BASE-BALL-GAME DEVICE.

1,268,436.

Specification of Letters Patent. Patented June 4, 1918.

Application filed October 14, 1916. Serial No. 125,591.

To all whom it may concern:

Be it known that I, FREDERICK J. CLARK, a citizen of the United States, and a resident of Syracuse, in the county of Onondaga and State of New York, have invented 5 a certain new and useful Base-Ball-Game Device, of which the following is a specification.

This invention has for its object a base 10 ball game device or board, and it consists in the features hereinafter set forth and claimed.

In describing this invention reference is had to the accompanying drawings in which 15 like characters designate corresponding parts in all the views.

Figure 1, is a plan view, partly broken away, of one form of my base ball game board.

20 Fig. 2 is a section taken on line 2—2, Fig. 1.

Fig. 3 is a fragmentary sectional view taken on line 3—3, Fig. 1.

This base ball game device comprises a 25 board provided with a surface having positions in which a ball or other object may lodge, indicating the result of the "out" team's defensive play and the "in" team's offensive play. It also preferably comprises means for impelling a ball onto the 30 field where it may lodge by chance in any one of said positions.

In this form of my invention the area of the board is divided into two fields, one 35 field having positions indicating the result of the "out" team's defensive play and the other field having positions indicating the result of the "in" team's offensive play.

1, designates the board which is supported 40 upon legs 2 so that it is slightly inclined from its upper end toward its lower end. 3 and 4 are respectively the fields having positions indicating respectively the "out" team's defensive play and the "in" team's 45 offensive play, and as here shown these fields are separated by a barrier 5 which extends from the lower end of the board and terminates short of the upper end of the board.

The means for impelling the ball onto 50 the field includes a spring-pressed manually operated plunger 6 movable in a socket or barrel 7 and having a handle 8 exposed on the lower end of the board, and in this embodiment of my invention 6, the socket and

the plunger are located on one of the lower 55 corners of the board as the lower right hand corner of the field 3.

A ball chute 8 extends from the socket 7 along the contiguous side of the board and along the outer side of the field 3, and means 60 are provided for directing the ball onto the respective fields 3, 4.

The means for directing the ball 9 when impelled by the plunger 6 from the chute 8, as here shown, includes a curved guide 65 10 extending the full width of the playing surface of the board and the ball chute 8, for guiding the ball 9 from the end of the chute 8 to the field 4, and a second displaceable guide 11 extending the width of the 70 field 3 and the chute, from the end of the barrier 5, for directing the ball from the chute 8 to the field 3 and preventing the ball from passing from the field 3 through the passage 12 between the end of the barrier 5 and the upper end of the board.

The field 3 for indicating the "out" team's defensive play is provided with suitable positions as sockets 13, on the field and pockets 14 at the lower end of the field, and also 80 with pins 15 for obstructing the ball and deflecting it so that the ball must take an irregular course from the upper end of the field to the lower end among the sockets 13. The sockets and pockets 13, 14 are designated 85 by initial letters F, B, S, and H, signifying respectively foul, ball, strike and hit.

The field 4 on which the result of the "in" or batting team's play is indicated, is provided with similar sockets 16, pockets 17, and pins 18, but preferably there are more sockets 16 in the field 4 than sockets 13 in the field 3, but the number and arrangement may be the same if desired. The sockets 16 90 and the pockets 17 are suitably designated by letters as O, E, HR, and 1, 2, 3, indicating respectively "out," error, home run, and 1st, 2nd, and 3rd base.

An additional socket 19 is also provided 100 in the passage 12 at the end of the barrier 5, this socket being normally provided with a cover 20 and being indicated by letters S B, signifying stolen base.

In operation the score is kept as in ordinary base ball on a score card and the player representing the "out" team first shoots the ball 9 by the plunger 6, out of the chute 8

against the guide 11 from which it rolls down the field 3 and lodges in one of the sockets 13 or pockets 14. If the ball lodges in the socket F it means that the result is 5 a foul, and if it lodges in a socket or pocket designated B or S, the result is a ball or a strike. Lodging of the ball in a socket or pocket H signifies that the player has struck the ball into fair territory and not that he 10 has made a base hit. Assuming that the ball lodges in a socket or a pocket of the field 3 designated H, the guide 11 is then removed and the other player, that is the player representing the "in" team, shoots the ball 9 from the chute 8 along the deflector or guide 10 into the field 4. If the ball 15 9 lodges in one of the O or "out" sockets or pockets 16 or 17, the "in" team has what in the outdoor game is one man out.

20 The deflector or guide 11 is again placed in position and the "out" team player again shoots the ball 9. The game then proceeds in like manner until three outs are scored, then the "out" team and "in" team positions 25 are reversed.

If an "in" team player lodges the ball in a socket or a pocket designated 1, 2, 3, or HR, on the field 4 the player has made a 1, 2, or 3 base hit or a home run, as the case 30 may be, the play being scored on the score card. Assuming that the ball lodges in a one base socket or pocket of the field 4 or it lodges four times when shot by the "out" team player in a socket or pocket designated 35 B of field 3, the "in" player in each case is credited with a man on first and the "out" player again shoots to the field 3. Assuming that the ball again lodges in an H socket or pocket, the "in" player now shoots to 40 field 4.

Assuming that the ball now lodges in the pocket designated 2, the "in" player is credited with a runner on third base and one on second base, the man credited on first base 45 being advanced two bases; and when the "in" player lodges the ball in positions of sufficient value to advance a runner to home plate, a run is scored on the score card. Likewise when the ball 9 after being shot 50 by the "in" player lodges three times on the socket or pockets 16, 17 designated O, the "in" or batting side is out. In case the batting side has what corresponds to two men out and a runner on third base, the player 55 may elect to remove the cover 20 of the socket 19, in which case a run is scored, if the player lodges the ball in the socket 19. If the ball misses this socket the "in" player is out. The "in" player may elect to use 60 the stolen base play at any other time. In fact the game is played in accordance with the practice of the outdoor game.

It will be obvious that the sockets and pockets may be arranged otherwise, and 65 that instead of two fields, one field may be

provided and the sockets therein provided with two designating characters one being used when the "out" team is shooting the ball, and the other when the "in" team is shooting.

What I claim is:—

1. A base ball game device comprising a board provided with two fields, one field having positions indicating the result of the "out" team's defensive play and the other 75 having positions indicating the result of the "in" team's offensive play, means for impelling a ball onto said fields, and means for guiding the balls to the respective fields, substantially as and for the purpose set 80 forth.

2. A base ball game device comprising a board provided with two fields, one field having positions indicating the result of the "out" team's defensive play and the other 85 having positions indicating the result of the "in" team's offensive play, a passage connecting the fields, means common to both fields for impelling a ball onto the fields, and a displaceable guide for confining the 90 movement of the ball to one of said fields when said guide is in operative position, substantially as and for the purpose described.

3. A base ball game device comprising a 95 board provided with two fields arranged side by side, a barrier separating the fields, the barrier having a passage therethrough for connecting the fields, one field having positions indicating the result of the "out" 100 team's defensive play and the other field having positions indicating the result of the "in" team's offensive play, and means for impelling the ball onto the fields, substantially as and for the purpose specified.

4. A base ball game device comprising a board provided with two fields arranged side by side, a barrier separating the fields, the barrier having a passage therethrough for connecting the fields, one field having 110 positions indicating the result of the "out" team's defensive play and the other having positions indicating the result of the "in" 115 team's offensive play, means for impelling the ball onto the fields, and a displaceable 120 guide arranged to guide the ball to one of said fields and prevent the ball from passing through the passage, substantially as and for the purpose set forth.

5. A base ball game device comprising a 120 board provided with two fields arranged side by side, a barrier separating the fields, the barrier having a passage therethrough for connecting the fields, one field having 125 positions indicating the result of the "out" team's defensive play and the other having positions indicating the result of the "in" team's offensive play, a starting chute for a ball extending alongside one of the fields, means for directing the ball from the chute 130

through the passage to the other of the fields, and a displaceable guide arranged to direct the ball onto the former field and prevent the ball passing through the passage, substantially as and for the purpose described.

6. A base ball game device comprising a board having two fields arranged side by side, a barrier separating the fields, the barrier having a passage therethrough for connecting the fields, one field having positions indicating the result of the "out" team's defensive play and the other having positions indicating the result of the "in" team's offensive play, a ball starting chute extending alongside one of the fields, and means for directing the ball from the chute to the respective fields, one of the directing means being displaceable and when in operative position being located to prevent the passing of the ball to the other directing means, substantially as and for the purpose specified.

7. A base ball game device comprising a board having two fields arranged side by side, a barrier separating the fields and extending from like ends of the fields and terminating short of the other ends, a chute extending alongside one of the fields, means for impelling the ball and along the chute through said passage to the other of the fields or into the former field, and guiding means for directing the ball to the respective fields, substantially as and for the purpose set forth.

8. A base ball game device comprising a board having two fields, one field having positions indicating the result of the "out" team's defensive play, the other having positions indicating the result of the "in" team's offensive play, a passage connecting the fields, means common to both fields for impelling a ball onto the fields, and a movable guide confining the movement of the ball to one of said fields, one of the positions of the "in" team's field being located in said

passage, substantially as and for the purpose described.

9. A base ball game device comprising a board having two fields arranged side by side, a barrier separating the fields, the barrier having a passage therethrough for dividing the fields, one field having positions indicating the result of the "out" team's defensive play and the other field having positions indicating the result of the "in" team's offensive play, a ball chute extending alongside one of the fields, means for directing the ball from the chute to the respective fields, one of the directing means being displaceable and when in operative position being arranged to prevent the passing of the ball to the other directing means, one of the positions of the "in" field being located in the passage at the end of the barrier, and means for impelling the ball along the chute onto the fields, substantially as and for the purpose specified.

10. A base ball game device comprising a board having two fields, a barrier separating the fields and extending from like ends of the fields and terminating short of the other ends of the fields, providing a passage connecting the fields, one field having positions indicating the result of the "out" team's defensive play and the other having positions indicating the result of the "in" team's offensive play, a starting chute for a ball opening into one of the fields, a curved guide extending the full width of both fields, the passage at one end of the barrier and the chute, and a removable guide extending from the barrier across one of the fields and the chute, substantially as and for the purpose set forth.

In testimony whereof, I have hereunto signed my name at Syracuse, in the county of Onondaga, and State of New York, this 5th day of Oct., 1916.

FREDERICK J. CLARK.
